UNITED STATES PATENT OFFICE.

WILHELM SCHUBBERT, OF BERLIN, GERMANY.

PROCESS OF MANUFACTURING WIGS.

SPECIFICATION forming part of Letters Patent No. 737,780, dated September 1, 1903.

Application filed December 23, 1902. Serial No. 136,363. (No specimens.)

To all whom it may concern:

Be it known that I, WILHELM SCHUBBERT, a subject of the King of Prussia, residing at Berlin, in the Kingdom of Prussia and German Empire, have invented certain new and useful Improvements in Processes of Manufacturing Wigs, of which the following is a specification.

The better class of wigs are usually manufactured by providing a foundation, preferably of silk-gauze, such as is employed for bolting-machines, and threading human hair through its meshes, the two materials being held together by knotting. The human skull, however, has approximately the form of a calotte. Even in the case of the smallest wig, or so-called "scalpette," therefore, the gauze must be given a more or less hollowed form, corresponding to the shape of the skull; otherwise the wig will not lie closely to the bald part of the head. For this reason the gauze after being given the desired form is generally provided with a small band at the periphery in order that the correct shape may be maintained. It is obvious that by this process a perfect and permanent fit is seldom attainable and is due to mere chance more than anything else, notwithstanding that the work of sewing the peripheral band to the gauze by hand is a delicate operation involving much tedious labor.

The subject of my invention is a new process of manufacturing wigs, according to which, while the peripheral band is dispensed with, a more perfect article is produced.

According to my new process the hairs are drawn singly through the gauze, (in place of which fine leather or other suitable material may be employed,) as hitherto. The material is then coated with a thick, but not necessarily saturated, solution of celluloid or caoutchouc or the like. The article thus treated is then laid while still wet upon the head and pressed down, so that it may take the form of the latter. It must then be left in this position until the solution is perfectly dry. For the purpose of promoting rapid drying the solution employed should be one of a volatile character. Thus if celluloid is used acetic ether would be the solvent most suitable from this point of view. This ether

has a pleasant odor and evaporates within a few seconds. After the solution has dried the wig can be removed from the head and will retain the hollow form without any further treatment or operation in this respect. The wig can be turned outside in, so that the hair lies inside the hollow, and again reversed into the proper position without the permanent shape of the wig being affected. Such reversal of the wig may, in fact, be repeated any number of times without the article losing its correct shape, unless, of course, the medium applied becomes dissolved or otherwise softened in some manner. Celluloid and caoutchouc being insoluble in cold or luke-warm water, (perspiration, &c.,) the wig will retain its shape for years.

The scalp of some persons is too sensitive to admit of the wig impregnated with a solution of celluloid or caoutchouc being applied to the head, owing to the sensation of cold thereby experienced at the bald part. In such cases the process may be modified, the celluloid solution being applied to the foundation of the wig, and after it has dried and the solvent totally evaporated, so that the celluloid has hardened on the gauze, the medium then rendered pliable and plastic by the aid of hot water or other suitable means. The still unshaped wig is then applied in warm condition to the bald part of the head and uniformly pressed down upon the latter with a gauze cloth or the like. The exact shape of the head will thus be imparted to the wig. The latter should be left in this position until it is perfectly cold, and when removed from the head it will permanently retain the assumed shape.

The process may also be employed for adapting a wig made for one person to the head of another wearer. Another advantage of the process is that the hair will adhere more firmly to the foundation in consequence of the impregnation and subsequent hardening of the latter with celluloid or caoutchouc. Wigs manufactured according to my improved process are practically indestructible. Furthermore, the wig after having been manufactured according to my method can be adapted to any special requirements in respect to the bald part of the head by cutting

the edges or subsequently shaping certain portions. This is impossible in the case of wigs shaped simply by the provision of a peripheral band. The edge of the wig can 5 also be cut in zigzag manner without any loss of hair in the neighborhood of the line of cut, so that the edge of the gauze, tulle, or other foundation, even in the case of very thinly knotted hair, is completely obliterated and 10 rendered invisible when the wig is in use.

What I claim as my invention, and desire to secure by Letters Patent, is—

1. The process of manufacturing wigs and the like, consisting in coating the foundation 15 of the article with a solution containing a hardening substance and a volatile liquid solvent, applying the thus-treated article to the bald part of the head and then removing it when the liquid solvent has evaporated and

the substance is hardened on the foundation, 20 substantially as described.

2. The process of manufacturing wigs and the like, consisting in coating the foundation of the article with a solution containing celluloid and a volatile liquid solvent, applying 25 the thus-treated article to the bald part of the head and then removing it when the liquid solvent has evaporated and the celluloid is hardened on the foundation, substantially as described. 30

In testimony whereof I have signed my name to this specification in the presence of two subscribing witnesses.

WILHELM SCHUBBERT.
